UNITED STATES PATENT OFFICE.

GEORGE CHURCH, OF AUCKLAND, NEW ZEALAND.

WEDGE.

1,209,262.

Specification of Letters Patent. Patented Dec. 19, 1916.

Application filed January 17, 1914. Serial No. 812,777.

To all whom it may concern:

Be it known that I, GEORGE CHURCH, a subject of Great Britain and Ireland, residing at No. 6 Haslett street, Eden Terrace, in the city of Auckland, Province of Auckland, and in the Dominion of New Zealand, general dealer, have invented a new and useful Wedge, of which the following is a specification.

10 My invention relates to improvements in wedges and more particularly to that class of wedges designed for the use of timbermen and others for splitting timber.

15 The object of this invention is to provide a simple, cheap, durable and effective wedge capable of exerting great power and of being readily and effectively driven in crooked and other timber, now frequently rejected, on account of its intense tenacity.

20 In carrying out my invention I impart to the construction of the wedge, a combination of a taper along both edges, as well as along the two faces, thus forming a long taper on all four sides, preferably extending the entire length of the wedge. A longitudinal twist or wind preferably extending the entire length of the wedge, also the rounded corners of same preferably extending the entire length of the wedge 25 and progressively decreasing in radius toward the point.

30 I attain these objects by the improved construction and shape given to the wedge which are illustrated in the accompanying drawing in which:—

35 Figure 1 is a front view showing the face of the wedge, constructed in accordance with my invention. Fig. 2 is a side view showing the edge of the wedge. Fig. 3 is an underview of the wedge projected from Fig. 1.

The wedge may be formed of metal or any other suitable material.

40 Similar letters refer to similar parts throughout the several views.

45 In Fig. 3 AAAA shows the head of the wedge and BBBB shows the chisel point of the wedge, thus showing by contrast in size the relative long taper on all four sides of the wedge. In Fig. 3 AAAA shows the 50 head of the wedge and BBBB the point of the wedge which is inclined to the sides of

the head, thus indicating the longitudinal twist or wind imparted to the construction of the wedge. In Fig. 3 CCCC shows the 55 rounded corners of the wedge. The curved lines ABAB in Figs. 1, 2 and 3 show the angles, corners or joinings of the faces and edges of the wedge. It can be readily seen that the influence of the twist in such a 60 wedge when it is being driven in, in the usual manner, by maul or other tool, tends to cause the embedded portion of the wedge to turn progressively around in a direction transverse to the original line of cleavage 65 and the rounded corners and tapers allow this to be done, thus producing a powerful reinforced action and rending strain.

The improved wedge has distinct advantages over the ordinary wedge, even if 70 used alone, but when used in conjunction with the ordinary wedge and they are driven alternately, its utility is very great, for the following reasons:—

75 The improved wedge has a great tendency by its progressive transverse action at the point to increase the power at the point and at the bottom of the substance under operation, whereas the ordinary wedge has the greatest power at the head of the wedge, 80 or at the top of the substance under operation, so that the effect of the wedges being used in conjunction, is to give a combined action, similar to and approaching to, the action of folding wedges when they are 85 driven from both ends.

It is to be understood that I do not strictly confine myself to the exact form or dimensions thereof, as long as I adhere to the principles of my invention as herein set 90 forth, variations of taper, twist and size, are necessary to meet the specific requirements of the various substances that are to be split, according to their tenacity or strength.

Having described the nature and objects 95 of the invention what I claim is:—

A wedge to which a longitudinal twist has been imparted through its whole length.

Dated this eighth day of December, A. D. 1913.

GEORGE CHURCH.
